UNITED STATES PATENT OFFICE

1,976,310

RHEOSTAT

Clifton M. Tuttle, Rochester, N. Y., assignor to
 Eastman Kodak Company, Rochester, N. Y., a
 corporation of New York

Application August 15, 1931, Serial No. 557,260

2 Claims. (Cl. 201—48)

My invention relates broadly to apparatus for varying the resistance of an electrical circuit, and more particularly to a method and means whereby a small modulation of energy in one circuit 5 may be utilized to vary a relatively large wattage in a second circuit.

One object of my invention is to provide an amplifying device whereby a small amount of energy may accurately control a relatively large 10 amount of power.

Another object of my invention is to provide an improved method and means for utilizing the moving elements of an electrical meter as a resistance controlling element.

15 Other objects of my invention will be understood from the following description when read in connection with the accompanying drawing in which like reference characters denote like parts throughout.

20 Fig. 1 is a front elevation of one form in which the resistance construction of my invention may be embodied.

Fig. 2 is a plan view partly diagrammatic of the entire apparatus.

25 Fig. 3 is a side elevation of the construction shown in Fig. 2.

Fig. 4 is a diagrammatic view showing a modified form of construction in which my invention may be embodied.

30 Fig. 5 diagrammatically illustrates one application of my invention wherein the resistance is employed to regulate the intensity of a light source in accordance with the transparency of a photographic film.

35 The principal part of my invention may be termed a variable resistance or rheostat and consists of a pair of insulated bars 10 and 11 upon which resistance elements comprising turns of wire 12 and 13 are wound. These bars are ar- 40 ranged side by side in parallelism and are normally spaced from each other as shown. A contact element 14 movable between and lengthwise of the bars 10 and 11 is adapted to control the number of turns of wire 12 and 13 connected be- 45 tween the terminal posts 15 and 16 in the following manner. With the bars spaced as shown the contact element 14 is freely movable to any position whereupon the bars may be moved toward each other as hereinabove described to grip 50 the contact 14 which electrically connects the wires 12 and 13 at that point to complete the circuit between the posts 15 and 16 and the number of turns of wire to the right of the contact 14 as shown in Fig. 1 will determine the amount 55 of resistance between these posts.

In Figs. 2 and 3 I have diagrammatically shown one arrangement for moving the contact 14 and for causing the bars 10 and 11 to grip this contact. The movable coil 17 of any suitable electrical instrument 17', here shown in outline, carries a vane 18 at the end of which is mounted the contact element 14 which may be of any suitable conducting material such as lead or silver. The bars 10 and 11 are curved to register with the path of the contact 14 and are mounted on one end of rods 19 by any suitable means such as headed studs 20. The rods 19 at their other end may be rotatably mounted on a small rod 21 and held in spaced relation thereon by a sleeve 22 and nuts 23. This rod 21 is mounted in stationary relation to the electrical instrument 17' in some suitable manner, and since there are numerous obvious ways of doing this, it is not now illustrated. Some suitable means such as springs 24 are employed to bias the bars 10 and 11 in contact gripping position. 60 65 70 75

Intermediate of their ends, the bars 19 are provided with cam surfaces 25 adapted to cooperate with cams 26 for separating the bars 19 against the tension of the springs 24. The cams 26 are rigidly mounted on the shaft 27 and may be rotated by turning a knob 28. The faces of the cams 26 farthest from the center are slightly flattened so as to be in stable position when turned to hold the bars 10 and 11 in spaced relation. 80 85

Instead of having both bars wound with wire as above described, my invention may take the form shown in Fig. 4. In this form the bar 30 is wound with resistance wire 32 and the bar 31 is a plain conductor. Also, the bar 30 varies in cross-section from end to end so that unit movement of the contact 14 from one end of the bars 30 and 31 acts to progressively insert less and less resistance. In other words, the resistance is varied as a function of the straight line movement of the contact 14. 90 95

From the above description it will be seen that my invention provides a rheostat having a slider or variable contact which is substantially frictionless and may be actuated by a delicate instrument sensitive to feeble currents. My improved rheostat may be employed in any electrical circuit where it is desired to vary the resistance of the circuit in accordance with variations outside of the circuit containing the rheostat. 100 For example, as illustrated in Fig. 5, the rheostat may be used for regulating the light intensity in photographic printing apparatus. In this figure the printing apparatus is illustrated employing a 105 110

printing lamp 40, a source of power 41 and a switch 42, all in series with my improved rheostat.

A negative 43 to be printed is placed between 5 a constant source of light 44 of predetermined intensity and a thermopile 45 connected with the movable coil 17 of the meter 17' to determine its density and therefore the printing light intensity necessary to properly expose a sensitive emulsion 10 through it in a known interval of time. The intensity of the light reaching the thermopile 45 and its consequent activation is a function of the density of the negative and will cause the coil 17 to rotate to bring the contact 14 into position 15 relative to the resistance member to insert the proper amount of resistance in the circuit of the lamp 40 to regulate its intensity to the value desired for printing a negative of such density. In order to avoid burning the contact element 14 20 I prefer to clamp the bars 10 and 11 on to it prior to closing the switch 42 and to open the switch 42 prior to moving the bars away from the contact 14. The switch 42 may be closed and opened by hand to time the exposure, or 25 any well known device may be employed to automatically control the interval during which the switch is closed.

My invention as described in connection with a photographic printer operates as follows: The negative 43 to be printed is placed between the lamp 44 and the thermopile 45 which causes the contact 14 to move to a position corresponding to the density of the negative, i. e., the activation 30 of the thermopile. The knob 28 is now turned to rotate the cam 26 to the position shown in Fig. 3 permitting the springs 24 to bring the wire turns 12 and 13 into pressed engagement with the contact 14. The negative is then placed 35 in printing position between a sensitive layer 46 and the printing lamp 40. Switch 42 is now 40

closed to energize the lamp and is opened after a predetermined interval of time which is preferably the same for all negatives, the exposure being governed by the intensity of the lamp 40.

It is to be understood that the application of my invention to a photographic printer is merely illustrative and is not intended to restrict it to said use alone since it is obvious that the meter may be actuated by any suitable current or potential and the rheostat may form a part of any electrical circuit in which it is desired to vary its resistance in accordance with the reading of any suitable indicating instrument.

While I have described my invention and certain limited embodiments, it is to be understood that my invention is not limited to the particular construction shown, but that various changes may be made within the scope of the appended claims without departing from the spirit of my invention.

What I claim as new and desire to secure by Letters Patent of the United States is:—

1. In combination, an electrical instrument having a part movable as a result of electrical variation, a conducting element carried by said movable part, an electrical circuit including two members electrically separated from each other and from said element and at least one member being of resistance material, means for urging said members into electrical contact with said element, and means for moving said members away from each other.

2. A variable resistance comprising in combination a pair of spaced insulated bars, resistance wire carried by each bar, a variable contact arranged to move between said spaced bars and means for moving said bars toward each other to bring said wire into engagement with said contact.

CLIFTON M. TUTTLE. 115
